PEDAL LIFT GATE

Park L. Newbold, Cedar Rapids, Iowa

Application November 21, 1947, Serial No. 787,463

2 Claims. (Cl. 39—44)

1

This invention relates to a pedal lift gate that opens upwardly.

It is the object of my invention to provide a gate of simple and inexpensive construction that will open with a slight pressure of the foot upon a pedal.

Another object of my invention is to provide a device that is balanced to such precision that very little effort is required for opening or closing.

Another object of my invention is to provide a gate that will open or close from either side without the operator moving from his place upon the ground.

Another object of my invention is to provide a gate of unusually long life due to being suspended in an upright position when in open position.

Another object of my invention is to provide a device to which existing gates may be attached for this novel way of operation.

Other and further features and objects of the invention will be more apparent to those skilled in the art upon a consideration of the accompanying drawings and following specifications, wherein is disclosed a single exemplary embodiment of the invention with the understanding, however, that such changes may be made therein as fall within the scope of the appended claims, without departing from the spirit of the invention.

Figure 1 is a view in perspective of my device in closed position and shows in particular, the balance weight, and suspending lever.

Figure 2 is a perspective view of the gate in open position and shows the balance weight floating adjacent to the ground.

Figure 3 is an enlarged view looking from the top showing the general frame arrangement and illustrating in particular the pivoted gate supporting member and pedal cross-shaft.

Figure 4 is an enlarged close-up view of the locking arrangement.

Referring now to the drawings a preferred embodiment of my invention includes a gate indicated generally at 10, a frame 11A and an opening and closing mechanism at 11.

The closing mechanism frame 11A is composed of side members 12 and 12A, auxiliary member 13 and cross members 14 and 14A. The gate 10 is secured to member 15 at 16 and is braced by 17. Member 15 is the main support of the gate and is pivoted in the frame members 12 and 12A at points adjacent their forward ends indicated at 18 and 18A. Member 19 to which the pedal levers 20 and 20A are secured is pivoted

2

in the side frame members 12 and 12A at points adjacent their rearward ends as indicated at 21 and 21A. The upright members 22 are attached to frame members 12 and 13 at 23 and braced by members 24 anchored at 24A. An elongated upper arm 25 is secured to a cross bar 26 which is pivoted in members 22 at 27 and 27A, a lower arm 28 is also secured to member 26 at 29 as shown in Figure 3 to form a compound lever, a lever arm 30 is attached to cross bar 15 at 31 and a link member 32 is pivotally connected to levers 28 and 30 at 30A. A weight 33 is suspended from lever 25 at 34 and a compensating spring 35 is pivotally attached to levers 28 and 30 at 28A to obtain a balance in opening and closing. A connecting member 36 is pivotally attached to lever 25 at 37 and to the pedal member 20 at 38 as shown by a dotted directional line in Figure 3.

20 Attached to the side frame members 12 and 12A and extending vertically are members 39 and 39A braced by members 40. Pivotally attached to the vertical members 39 and 39A are angular shaped handles 41 and 41A their outer ends 43 being adapted to link with cooperating members 20 and 20A by means of members 43A pivotally attached at 42 and 42A. A locking arrangement shown in Figure 4 and indicated at 44 and 44A is attached to the upper extremities of members 39 and 39A and operates from either side of the gate by moving one of the pins 44 or 44A into an opening in the gate shown at 45, while an additional opening 46 is provided so that the outer end of the gate may be locked in a raised position to permit hogs or other small stock to pass under. Posts between which the outer end of the gate 10 rests are shown at 47. Foot contact members are attached to the free ends of the pedal levers 20 and 20A as shown at 48 and 48A. Where references are made as to members being attached or secured to other members it is understood that any of customary methods may be used for this purpose.

In use, the operator may be on either side of the gate as duplicate controls are provided. To raise, one places his foot on pedal 48 and pushes downward; this causes a pull on the connecting link 36, a rearwardly movement of lever 28 and cooperating lever 30, a lowering of the balance weight 33, an inward movement of the handles 41 and the subsequent raising of the gate 10 to an upright position and the expansion of the compensating spring 35. To lower, one grasps handle 41 and pulls forward, being connected to pedal levers 20 as shown at 42 and 43, this effects a

reverse action and raises the pedals 48 and lowers gate 10 to closed position. To lock gate in position one moves sliding pin 44 into place.

I claim as my invention:

1. In a pedal lift device, the combination of a frame composed of cross members and parallel side members secured together, a main shaft cross member pivoted in the parallel side members at points adjacent to their forward ends, a gate secured to the pivoted shaft, another cross shaft pivoted in the parallel side frame members at points adjacent to their rearward ends, a pair of pedal levers attached thereto, a pair of upright frame members supporting a pivoted compound lever, a weight attached to the elongated upper arm of the lever, an operating lever secured to the main cross shaft at a point adjacent to the gate, a connecting member between the operating lever and the lower section of the compound pivoted lever, a compensating spring also engaged thereto, a connecting member between the elongated upper arm of the compound lever and one of the pedal levers, a pair of handle levers pivoted on upright members secured to the forward part of the frame, and connecting members between said handle levers and the pedal levers substantially as described.

2. The combination, with a frame, of a gate secured to a lever member pivotally attached to said frame, a pair of pedals and a pair of handles adapted to actuate same by means of a compound lever pivotally attached to supporting upright members, and connecting members between said compound lever, pedals, gate securing lever member and handles, a balance weight attached to the compound lever, a compensating spring engaged to the compound lever and to the gate supporting lever member, and a pair of sliding pin locking members placed adjacent to the handles and adapted to fit within apertures in the gate, substantially as described.
